UNITED STATES PATENT OFFICE

RUDOLPH S. NELSON, OF ROCKFORD, ILLINOIS, ASSIGNOR TO THE HOOVER COMPANY,
OF NORTH CANTON, OHIO, A CORPORATION OF OHIO

METHOD OF AND APPARATUS FOR PRODUCING REFRIGERATION

Application filed May 24, 1930. Serial No. 455,211.

This invention relates to the art of refrigerating and more particularly to continuous absorption refrigerating systems in which a plurality of refrigerants are simultaneously evaporated to produce a cooling effect.

Continuous absorption refrigerating systems employing a single refrigerant in combination with an inert or neutral gas are well known. In such a system the inert gas is circulated between the evaporator and the absorber and in accordance with Dalton's laws of partial pressure maintains the total pressure in these parts the same as that in the other parts of the system although the partial pressure of the refrigerant is lower in the evaporator and the absorber than in the condenser and boiler. An example of such a system is found in the U. S. patent to Geppert 662,690 of Nov. 27, 1900. As an improvement on this system it has previously been proposed to substitute a second refrigerating agent for the inert gas of the Geppert system so that both the main cooling agent and the auxiliary pressure equalizing agent may be condensed before they are introduced into the evaporator, the object being to increase the efficiency and the cooling effect of the system. Perhaps the best substances suggested for this purpose are ammonia and propane, these two refrigerants being condensable at about the same temperature and pressure and being practically immiscible.

Now if two refrigerants are to be condensed at one temperature and evaporated, each in the presence of the vapor phase of the other, at a lower temperature to produce a cooling effect, it is clear that they must be effectively separated before they can again be condensed at the higher temperature, there being no material difference in total pressure throughout the system.

One way of separating them is effected by causing the gaseous mixture of the two refrigerants to come into contact with a solvent for one of them. In the case where ammonia and propane are used as the refrigerants, water may be used as the solvent since it

readily absorbs the ammonia but not the propane.

In attempting to operate a refrigerating machine on this principle, difficulty has been experienced because of the fact that the auxiliary agent has condensed in parts of the apparatus where it is desired and intended that it be in a vapor or gaseous state. For example, in attempting to operate apparatus heretofore proposed for carrying out the above principle in which an absorber and two condensers, one for the main refrigerant, and one for the auxiliary refrigerant, were provided, it has been found that the auxiliary agent condensed in the absorber instead of the condenser provided for that purpose.

In order to make the machine operate, it is necessary to vaporize the liquefied auxiliary agent collected in the absorber. Where ammonia and propane are used as the refrigerants, the propane liquid floats on top of the solution in the absorber. By carefully controlling the circulation of the solution, just the right amount of heat may be carried by convection from the heater for the boiler to the absorber to drive off this liquid propane. This requires the use of pipes of certain dimensions and the supply of heat to the boiler must be just right for these requirements. If too much heat is carried to the absorbers, the solution does not properly absorb the ammonia. If too little is carried thereto, the liquid propane is not vaporized.

In order to overcome these and other difficulties, an object of the present invention is to provide novel means for heating the absorber to the required temperature in the zone occupied by the liquefied auxiliary agent while maintaining the remainder of the absorber cold so as to facilitate absorption of the main refrigerant.

A further object is to provide novel means for maintaining predetermined temperature conditions in the absorber of a refrigerating system adapted to employ a plurality of refrigerants.

Another object resides in the arrangement of valves for charging refrigerating apparatus designed to employ a plurality of refrigerants whereby a column of the auxil-

iary agent may be formed artificially before the apparatus is put into operation.

Further objects reside in the methods of producing refrigeration and of effectively 5 separating two refrigerants.

Other objects and advantages reside in certain novel arrangements and construction of parts as will be apparent from the following description taken in connection with the 10 accompanying drawing in which—

The single figure is a diagram of an absorption refrigerating system embodying certain novel features and illustrating one form of apparatus adapted to carry out the 15 principles of the invention.

Referring to the drawing, the system is there shown as consisting of a generator or boiler G, rectifier R, condensers C₁ and C₂, evaporator E, absorber or separating vessel 20 A, heat exchanger H and the temperature regulating coil T, these vessels being connected by suitable conduits as shown. All of the parts may be made of steel. In general they are cylindrical in shape so that 25 ordinary seamless steel tubing may be used in manufacturing them. For purposes of description, it will be assumed that the apparatus is charged with ammonia, propane and water, although the invention is not 30 limited to the use of these fluids.

The generator G comprises a hollow shell having end closures or heads 11 and 12 at the top and bottom thereof. The lower end 12 is provided with an inverted cup 13 which 35 is welded or otherwise secured to an opening therein and which is adapted to receive an electric cartridge heating element 14. Obviously a gas flame or other heating means may be employed in place of the electric 40 heater.

In normal operation a solution of ammonia circulates through the generator. For conducting the solution into the generator a pipe 15 extends through the lower end 12 45 of the generator proper and is connected to a small coil of tubing 16 which is wrapped around the inverted cup 13. The upper end of the coil 16 is connected to a vertically extending pipe 17 which may be reversely bent 50 at its upper end as shown. By this means when current passes through the electric heater 14, bubbles of ammonia gas are generated in the coil 16 and as they rise through the pipe 17 lift or pump the solution to the main 55 body of the generator. A similar arrangement of a gas lift pump in a refrigerating system is shown and described in the U. S. patent to Altenkirch 1,728,742.

In addition to the ammonia gas generated 60 in the gas lift pump, an amount is driven off by the application of heat to the main portion of the generator. The expelled gas passes upwardly through an opening in the closure 65 11 and into the rectifier R which is provided

with suitable baffles as shown for removing water vapor which is driven off with the ammonia. The upper end of the rectifier is connected to condenser C₁ through the pipe 21. As ammonia is driven off from the solution in the generator the weak solution is conducted away through the conduit 23. 70

The condensers C₁ and C₂ referred to above may be of any suitable construction. For the purposes of illustration they are shown as 75 consisting of a small pipe coiled inside of a larger one through which cooling water is adapted to circulate. The inner pipes are indicated by the reference characters 24 and 25 on the drawing while the cooling jackets 80 are indicated by the numerals 26 and 27.

For reasons which will be more apparent from the description which is to follow as to the operation of the system, it is important that the inner pipes 24 and 25 of these condensers be of small diameters preferably not over a quarter of an inch inside diameter. The condensers, and particularly the propane condenser, should be located a considerable distance above the evaporator so that fluid 85 columns may form in the lower portions of the pipes 24 and 25. It is desirable that the propane condenser be located sufficiently high that the distance between the lower portion thereof and the top of the evaporator may be 90 at least two and one half times the height of the liquid in the absorber A. It may be desirable to extend the cooling jackets 26 and 27 over the lower portions of the pipes 24 and 25 under some conditions. On the drawing 95 the pipes connected to the condensers are shown broken so as to save space in illustrating.

The evaporator E is so constructed that 100 liquids entering through the pipes 24 and 25 do not mix so long as they are in their liquid phases but each liquid is exposed to the vapor phase of the other. For a full disclosure of 105 this evaporator and the manner in which it operates reference may be had to my co-pending application, Serial No. 423,125, filed January 24, 1930 for "evaporators for refrigerating systems." As herein shown it consists of 110 a cylindrical shell 29 having end closures or heads 30 and 31. The pipes 24 and 25 extend through the shell 29 near the upper end. Each of the pipes 24 and 25 has a U-shaped 115 bend therein to provide a liquid seal immediately outside the evaporator. The U-bend in the pipe 25 is provided with valves 32 and 32'. Liquids entering the evaporator through the pipes 24 and 25 trickle down over separate 120 sets of baffle plates indicated by the numerals 33 and 34 so that each liquid is exposed to the vapor phase of the other. This causes evaporation accompanied by the extraction of heat from the surroundings to produce a cooling effect. The vaporized fluids are conducted out of the evaporator through a conduit 35 connected to the lower end piece 31. Any 125

Liquid which may have been supplied to the evaporator and not vaporized is also drained away through the pipe 35.

The absorber or separating vessel A consists merely of a cylindrical drum made up of a shell 36 and end pieces 37 and 38. It may be cooled by circulating water through the coil 40 secured to the shell 36. A perforated baffle plate 39 is situated near the lower 10 end immediately above the point where the pipe 35 is connected to the absorber. The upper end of the absorber is connected to the upper end of the condenser C₂ by means of a pipe 41, this pipe being of larger diameter 15 than that of the conduit or pipe 25 of the condenser. An upper horizontal portion of the pipe 25 has two valves associated with it, one, designated 42 for preventing the passage of fluid between the pipes 25 and 41 and another, 20 designated 43 for opening the pipe 25 to the atmosphere or to a charging cylinder when desired.

For supplying absorption liquid to the absorber a conduit 44 is connected to the shell 25 36 as shown.

Adjacent the absorber a portion of this pipe together with a larger one 45 is formed into a coil, the pipe 45 providing a jacket for a certain portion of the conduit 44. Water 30 of a predetermined temperature may be circulated through the jacket 45 so that the absorption solution delivered to the absorber may have a definite temperature. The lower end of the conduit 44 is connected to the 35 outer jacket 46 of the heat exchanger H, the upper end of the jacket 46 being connected to conduit 23.

For use in starting, or if desired for continuously heating the upper part of the absorber during operation an electrical heating coil 47 surrounds a portion of the absorber immediately above the inlet pipe 44. The amount of current flowing through this coil may be controlled by any suitable means, 45 (not shown) in order to maintain any desired temperature in this part of the absorber.

For conducting the absorption solution away from the absorber, the pipe 15 which is connected to the coil 16 of the boiler and 50 which forms the central pipe of the heat exchanger H is connected to the lower head piece 38 of the absorber.

There are three cycles for fluid circulation provided by this construction. One cycle 55 which may be termed the ammonia cycle takes place from the generator G through the rectifier R, pipe 21, condenser C₁, evaporator E, absorber A, conduit 15, gas lift pump 16 and pipe 17 back to the generator.

Another 60 cycle which may be called the propane cycle takes place from the absorber A through the pipe 41, valve 42, pipe 25 of the condenser C₂, valve 32, evaporator E and pipe 35 back to the absorber. The third cycle which may 65 be called the solution cycle takes place be-

tween the generator and the absorber, the circuit being from the generator through conduit 23, outer coil 46 of heat exchanger H, conduit 44, the absorber A and back to the generator through the conduit 15, coil 70 16 and pipe 17.

The apparatus may be charged and operated as follows:

A quantity of ammonia solution is placed in the generator G and absorber A through 75 suitable valves not shown, until the same has filled these vessels up to approximately the levels shown by the dotted lines. The concentration of the ammonia solution used should be low and should be preferably even 80 lower than 15% of ammonia by weight. Air may then be swept out of the apparatus in the usual manner, by forcing ammonia gas into the generator and absorber, the valves 32, 32', 42 and 43 being open at this time. 85 A quantity of liquid propane may then be placed in the absorber or in the condenser C₂. The quantity of propane placed in the system should be sufficient to insure the formation of a column of liquid in the pipe 25 90 and cover the plates 33 in the evaporator. As a factor of safety slightly more than this quantity may be added because of the fact that the condenser C₂, evaporator and top portion of the absorber will be filled with propane vapor during the operation of the machine and a quantity of liquid propane remains in the absorber. The valves 32, 32', 42 and 43 provide means for artificially forming a column of propane in the pipe 25 95 100 as an initial step should this be necessary. To form this column a cylinder filled with propane under pressure is connected to the outlet pipe of the valve 32', the valves 32 and 43 are closed and the valve 43 cracked 105 slightly. Propane then flows into the pipe 25. The charging valves to the generator and absorber and the valves 32' and 43 may then be closed, the valves 32 and 42 opened and heat applied to the generator thus causing delivery of ammonia gas to the condenser C₁ and the formation of a column of liquid ammonia in the conduit 24. It may be necessary, especially if the liquid propane has been charged into the absorber to apply heat 110 115 to the top portion of the absorber at this time by means of the electric heater 47 or otherwise to drive the propane into the condenser C₂. During these initial steps cooling water should be circulated through the jackets 26 120 and 27 around the condensers and through the coil 40 around the absorber.

In order to provide for the delivery of propane from the absorber A to the condenser C₂ it is necessary to maintain at least the upper 125 portion of the absorber at a temperature higher than that of the condenser C₂. Under normal operating conditions this difference in temperature should be at least 20 degrees F. Since the efficiency of the absorption of 130

ammonia is dependent upon the lower portion of the absorber being cool, cooling water should of course be circulated through the coil 40. If the machine is operated in a warm room the effect of air circulating around the top portion of the absorber should be taken into consideration, and if the area of the absorber is sufficiently large as compared with the amount of solution therein, warm air alone may be sufficient to maintain the necessary temperature difference. Preferably the heat of the atmosphere should not be relied upon for this purpose, however and means has been provided for accurately controlling the temperature of the upper part of the absorber. Either the temperature regulating coil T or the electric heater 47 or both may be used for this purpose. The water entering the absorber through the pipe 44 is normally warmer than that leaving through the pipe 15 so that the coil T need not effect a radical change in temperature conditions in the pipe 44, but it is very useful in maintaining uniform and optimum temperature conditions in the absorber.

It has been found that a machine constructed like that illustrated operates to produce a cooling effect when the cooling water to the condensers and the coil 40 on the absorber is at a temperature of between 50 and 55 degrees F. while that supplied to the jacket 45 of the coil T is between 80 and 90 degrees F. Under these conditions the two refrigerants condense in their respective condensers, form columns in the pipes 24 and 25 and flow into the evaporator. As the refrigerants trickle down over the plates provided in the evaporator, vaporization of both takes place, the vapor of each refrigerant exerting its pressure independently of the other so that although the total pressure in the evaporator is only slightly greater than elsewhere in the system, the partial pressure of each refrigerant vapor is less. As vaporization takes place initially the pressure in the evaporator rises slightly.

This excess pressure becoming large enough to overcome the liquid column head in the absorber, bubbles of ammonia and propane are forced into the lower portion of the latter through the pipe 35. As these bubbles mix with the weak solution coming to the absorber through the pipe 44, both refrigerants are changed to a condensed fluid phase, that is, the ammonia is absorbed and the propane condensed. As the propane rises, it is heated as explained above and passes in gaseous form through the conduit 41 into the condenser C₂ where it is again condensed to complete its cycle.

The ammonia which is absorbed in the solution in the absorber is conducted through the pipe 15 into the generator through the gas lift pump 16 from which it is again expelled

in gaseous form into the condenser C₁ to complete its cycle.

The solution thus deprived of ammonia returns to the absorber or separator through the pipe 23, jacket 46 of the heat exchanger and the pipe 44, as explained above.

Since it is impossible to absorb all the ammonia some will remain in a gaseous state and pass with the propane into the condenser C₂. Unless ammonia is removed from the condenser it will collect there until its partial pressure at this point is about the same as that in the evaporator, under which conditions it would of course be impossible to condense propane in the condenser C₂ and evaporate it in the evaporator at a lower temperature. Some means must therefore be provided to remove the ammonia from the condenser C₂. If the pipe 25 is sufficiently small in diameter this difficulty may be overcome by causing the propane, which will condense in the condenser C₂ even in the presence of a small amount of ammonia gas, to form slugs which completely fill the pipe 25 and act as pistons to carry along bubbles of ammonia as it passes downwardly through the pipe 25 into the evaporator. If any propane gas should find its way into the ammonia condenser C₁, it will be removed therefrom in the same way.

It will thus be seen that a refrigerating system has been provided in which two refrigerants are simultaneously evaporated and are then separated so that they may be condensed in their respective condensers.

Since the drawing is only diagrammatic in nature it is obvious that in constructing an apparatus in accordance with the principles of the invention, various expedients may be resorted to and various changes may be made in the arrangement and construction of the various parts without departing from the spirit of the invention. The vessels may be made of different shapes and dimensions so long as they do not interfere with the intended circulation and liquid levels. It is also within the scope of the invention to regulate the flow of fluids in any of the various pipes by the provision of valves or restricted portions or the like. Various other expedients may be resorted to without departing from the spirit of the invention or the scope of the annexed claims.

I claim:

1. Refrigerating apparatus adapted to produce cooling effect by the evaporation of ammonia and propane including an evaporator in which said ammonia and propane may simultaneously evaporate, an absorber in which the ammonia may be absorbed by an absorption liquid, means for cooling the lower portion of the absorber, and means for heating the upper portion of the absorber to vaporize liquid propane therein.
2. Refrigerating apparatus adapted to

produce cooling effect by the evaporation of ammonia and propane including an evaporator in which said ammonia and propane may simultaneously evaporate, an absorber 5 in which the ammonia may be absorbed by an absorption liquid, means for cooling the lower portion of the absorber, and means for heating the upper portion of the absorber to vaporize liquid propane therein, said heating means including conduit for conveying absorption liquid to the absorber and a jacket surrounding a portion of said conduit through which water at a predetermined 10 temperature may be circulated.

15 3. Refrigerating apparatus adapted to produce cooling effect by the evaporation of ammonia and propane including an evaporator in which said ammonia and propane may simultaneously evaporate, an absorber in 20 which the ammonia may be absorbed by an absorption liquid, means for cooling the lower portion of the absorber, and means for heating the upper portion of the absorber to vaporize liquid propane therein, said heating means including an electrical resistance conductor surrounding the upper portion of 25 said absorber.

4. Refrigerating apparatus adapted to produce cooling effect by the evaporation of a 30 main refrigerant and an auxiliary refrigerant, said apparatus including an evaporator in which said refrigerants may evaporate, an absorber in which the main refrigerant is absorbed by an absorption liquid, a generator 35 for expelling the main refrigerant from the absorption liquid, a condenser for said main refrigerant connected between said generator and said evaporator, a condenser for said auxiliary refrigerant connected between 40 said absorber and said evaporator and means for causing the auxiliary agent to pass through a cycle in which it is vaporized in the evaporator, liquefied in the lower portion of the absorber, again vaporized in the upper 45 portion of the absorber, again liquefied in the condenser and returned to the evaporator.

5. Refrigerating apparatus adapted to produce a cooling effect by the evaporation of a main refrigerant and an auxiliary refrigerant, said apparatus including an evaporator 50 in which said refrigerants may evaporate, an absorber in which the main refrigerant is absorbed by an absorption liquid, a generator for expelling the main refrigerant from the absorption liquid, a condenser for said 55 main refrigerant connected between said generator and said evaporator, a condenser for said auxiliary refrigerant connected between said absorber and said evaporator and means 60 for causing the auxiliary agent to pass through a cycle in which it is vaporized in the evaporator, liquefied in the lower portion of the absorber, again vaporized in the upper portion of the absorber, again liquefied in the condenser and returned to the 65

evaporator, said means including a device for cooling fluids in the lower portion of the absorber and a device for heating fluids in the upper portion of the absorber.

6. In an absorption refrigerating system 70 employing two refrigerants, an absorber, means for conducting a gaseous mixture of the refrigerants into said absorber, means for conducting a solvent for one of said refrigerants into said absorber and means for heating one portion and cooling another portion of said absorber.

7. In an absorption refrigerating system 75 employing two refrigerants, an absorber, means for conducting a gaseous mixture of the refrigerants into said absorber, means for conducting a solvent for one of said refrigerants into said absorber and means for maintaining the upper portion of said absorber at a higher temperature than the lower portion thereof.

8. In refrigerating apparatus adapted to employ a plurality of refrigerants, the combination of an evaporator, a plurality of condensers situated above said evaporator, an absorber, conduits for conveying one of said refrigerants in a cycle through said absorber, one of said condensers and said evaporator back to said absorber, a valve located in the conduit from said absorber to 95 said condenser, a second valve located in the conduit from said condenser to said evaporator and a valve connected to each of said conduits and adapted to open the same to the atmosphere or to a charging device whereby 100 a column of liquid refrigerant may be artificially formed in said condenser and in the conduit from said condenser to the evaporator before the machine is placed in operation.

9. In absorption refrigerating apparatus adapted to employ a main refrigerant and an auxiliary pressure equalizing agent, the combination with an absorber, a condenser, an evaporator and conduits connecting the same, of means for circulating said auxiliary agent between said absorber, condenser and evaporator, said means including a device for cooling the lower portion of the absorber, a device for heating the upper portion of the absorber and a device for cooling said condenser whereby said auxiliary agent will be caused to condense in said absorber and evaporate therefrom and again condense in said condenser.

10. In refrigerating apparatus employing a main refrigerant and an auxiliary pressure equalizing agent and having an evaporator and an absorber, the method of circulating the auxiliary pressure equalizing agent between the absorber and the evaporator which consists in vaporizing the agent in the evaporator, liquefying the same in the absorber, applying heat to a portion of the absorber to vaporize the auxiliary agent and condensing 125

the auxiliary agent at a level above the evaporator whereby it may flow back into the evaporator by gravity.

11. In an absorption refrigerating system employing two refrigerants, the combination of an evaporator wherein both of said refrigerants may evaporate, a separating vessel, a conduit for conveying the vaporized refrigerants from said evaporator to said separating vessel, a generator, means for circulating an absorption solution between said generator and said separating vessel to convey one of said refrigerants to said generator, means for cooling a portion of said separating vessel to cause the other of said refrigerants to condense therein and form a layer on top of the absorption solution therein, means for heating said generator and a portion of said separating vessel to vaporize the refrigerants and means for condensing said refrigerants and returning them to said evaporator.

12. In a refrigerating system of the absorption type employing two refrigerants, means for causing one of said refrigerants to pass through a cycle in which it is separated from an absorption solution by the application of heat, condensed, evaporated to produce a cooling effect and returned to the absorption solution and means for causing the other of said refrigerants to pass through a cycle in which it is vaporized from a liquid phase by the application of heat, condensed and evaporated with the first mentioned refrigerant for the production of cooling effect and again changed to a liquid phase.

13. In a refrigerating system employing a plurality of refrigerants, a vessel for separating said refrigerants after they have become mixed and means for heating a portion of said vessel to vaporize one of said refrigerants.

14. In an absorption refrigerating system employing a plurality of refrigerants, a vessel for separating said refrigerants and means for heating a portion of said vessel to vaporize one of said refrigerants, said means including a conduit adapted to convey an absorption solution to a portion of said vessel.

15. The method of producing refrigeration including the steps of feeding a plurality of refrigerants in liquid phase into an evaporator, conducting the vaporized refrigerants from the evaporator into a separating vessel, changing the refrigerants to more dense fluid phase in said vessel and separating the same by gravity.

16. The method of producing refrigeration including the steps of feeding two different refrigerants in liquid phases into an evaporator, conducting the vaporized refrigerants from the evaporator into a separating vessel, changing the refrigerants to more dense fluid phase in said vessel, separating the same by gravity, vaporizing each refrigerant after it has been separated from the other,

condensing said refrigerants separately and again feeding them into the evaporator.

17. A refrigerating system including two refrigerants, a solution adapted to absorb one of said refrigerants but not the other and having a different specific gravity than the refrigerant not absorbed, an evaporator in which both of said refrigerants evaporate to produce cooling effect, a separating vessel, means for conducting a vapor mixture of said refrigerants into said vessel, means for circulating said solution through the separating vessel to thereby cause the solution to absorb one refrigerant so that the other may condense in said vessel and separate from the solution by gravity and means for returning the refrigerants so separated into the evaporator in liquid form.

Signed at North Canton, in the county of Stark, and State of Ohio, this 20th day of May, 1930.

RUDOLPH S. NELSON.
